THE COLUMBIA PLANOGRAPH CO., WASHINGTON, D. C.

UNITED STATES PATENT OFFICE.

JAMES T. JOHNSON, OF CHICAGO, ILLINOIS.

AUTOMATIC SPARK-ARRESTER FOR SAWS.

1,312,121.

Specification of Letters Patent. Patented Aug. 5, 1919.

Application filed August 2, 1917. Serial No. 184,178.

To all whom it may concern:

Be it known that I, JAMES T. JOHNSON, a citizen of the United States, residing at Chicago, in the county of Cook and State 5 of Illinois, have invented certain new and useful Improvements in Automatic Spark-Arresters for Saws, of which the following is a specification.

This invention relates to new and useful 10 improvements in automatic spark arresters for saws.

The primary object of the invention is the provision of an inexpensive device adapted for employment in connection with any saws 15 which produce sparks during the operation thereof, the construction being such that by pneumatic and magnetic control of the sparks thrown off by the saw, the safety of the workmen as well as the adjacent property is fully safeguarded.

A further object of the device is the provision of a spark collector for rotary saws employed with steel mill machinery such as rolling, blooming and rail mills as well 25 as structural mills, whereby the sparks thrown off in sawing either hot or cold metals will be automatically collected and the attendants permitted to remain near the saw during the cutting operation regardless 30 of the excessive heat generated by the saw.

A still further object is the provision of a magnetic and pneumatic spark controlling and collecting means for rotary metal-saws whereby the saw will have greater efficiency 35 and the operatives will be fully protected.

With these general objects in view and others that will appear as the nature of the invention is better understood the device consists of the novel combination and arrangement of parts hereinafter fully described, and illustrated in the accompanying drawings and pointed out in the appended 40 claims.

In the drawings forming a part of this 45 application and in which like designating characters refer to corresponding parts throughout the several views,

Figure 1 is a side elevation of the device operatively arranged in connection with the 50 one form of rail cutting saw.

Fig. 2 is a top plan view thereof.

Fig. 3 is a front elevation of the same.

Fig. 4 is a vertical sectional view taken through the device.

Fig. 5 is an elevational view of the auto- 55 matic controlling means for the magnetic and pneumatic mechanism and

Fig. 6 is a vertical sectional view taken through Fig. 5.

Fig. 7 is a detail view showing the fol- 60 lower mechanism for the casing and

Fig. 8 is a vertical sectional view through the device.

Referring more in detail to the drawings, it will be first understood that the device 65 is adapted for employment with any form of saw such as the circular rail cutting saw 10 having a sharpened periphery 11, the saw having a central operating shaft 12 adapted for swinging movement mounted by 70 means of an arm 13 depending from a suitably located support 14. A cylindrical casing 15 preferably formed of thin metal is arranged around the saw 10 and journaled upon the shaft 12 being supported for simul- 75 taneous swinging movement with the saw by means of cords 16 and 17. The cord 16 is attached to the forward side of the casing 15 as at 18 and to a stationary post 19 rearwardly of the casing while the cord 17 80 is attached to the rear side of the casing as at 20 and to a lever 21 by means of which the saw is adapted to be shifted as at 22. It will be understood that both of the cords 16 and 17 pass over a roller 23 carried by 85 the arm 13 while a link 24 operatively connects the lever 21 with the arm 13.

It will be understood that by means of this construction, the lever 21 which is pivoted at 25 may be shifted by means of the handle 90 26 at the bottom thereof for moving the casing 15 and the saw 10 in a swinging movement forwardly to the dotted line position shown in Fig. 1.

A trough 27 is supported stationarily 95 with the casing 15 arranged for swinging movement therein, a curved follower 28 being arranged through the slotted bottom of the trough 27 for engaging the casing 15. The follower 28 is arranged with a hub 29 100

5 journaled upon a shaft 30 while the spring 31 is tensioned between the wheel 32 of the follower and a stationary member 33 for maintaining the follower against the rear side of the casing and assisting the forward movement of the latter as illustrated by dotted lines in Fig. 1 of the drawings.

10 The casing 15 is preferably arranged with one side 34 thereof hinged as at 35 to the main portion of the casing while the side 34 is formed in two semi-circular sections connected together by hinges 36.

15 The trough 27 within which the casing 15 freely swings is formed in two parts which may be connected together in any desired manner such, for instance, as being mounted upon the electro-magnet 37 which is employed for collecting the sparks which magnet thereby forms a portion of the closed 20 bottom of the trough 27, the sides of the trough being secured to the magnet in removable manner by means of hold-fast devices such as bolts 38. It will be understood that the electro-magnet 37 and the trough 25 27 may be mounted in any desired manner, it being understood that the sparks from the saw 10 will be attracted and collected by the electro-magnet 37 at the bottom of the trough as well as by the forwardly positioned basin 39 carried by the said trough. A saw-run 40 of the usual miter-box form is arranged through the basin 39 and provided with transverse slots 41 through which the saw 10 is passed in cutting metal, such 30 as rails and steel bars longitudinally moved through the run 40.

35 The opposite sides of the casing 15 are cut away as at 42 permitting the cutting edge 11 of the saw 10 to be exposed for cutting the metal within the run 40, it being noted that this cut-away portion forms a mouth in the casing 15 which receives the run 40 and permits the saw 10 to operate through the adjacent slot 41 of the run when 40 such slot is arranged within the basin 39, it being understood that the latter is suitably channeled for the reception of both casing and saw. Receiving sockets 43 are provided in the upper edges of the trough 27 adapted 45 to receive slide plates 44 for covering up the cut-away portions 42 and preventing the escape of the sparks therethrough.

50 The hood 45 is hinged as at 46 to the forward end or nose 47 of the basin 39 being 55 normally maintained in its closed position by means of a leaf spring 48 and overlying the run 40. A finger 49 is carried by the casing 15 forwardly of the cut-away portion 42 projecting within the hood 45 for 60 raising the hood by contact of the finger with the hood as the saw and casing move forwardly while a handle 50 is also provided for the hood.

A compressed air pipe 51 is arranged for

blowing forwardly toward the electro-magnet 37, the sparks which are generated by the saw 10 and a multiple nozzle 52 is arranged within the casing 15 upon either or both of the sides thereof adjacent the saw connected to the pipe 51 by means of a flexible hose 53. It will be understood that the sparks flying rearwardly will be met by the forward current of air from the nozzle 52 being thereby baffled and caused to fall within the influence of the electro-magnet 37, as well as being partly cooled by the air prior to their deposit upon the magnet as well as within the basin 39.

It is designed to maintain the electrical current in connection with the electro-magnet 37 for energizing the magnet simultaneously with the supply of air to the nozzles 52 and this is automatically accomplished by the mechanism best illustrated in Figs. 7 and 8 of the drawings. The aforementioned shifting lever 21 has an upward extension 54 having an arcuate movement adjacent a curved segment 55, while the said segment has a transmission plate 56 extending partially the length of the segment and upon the opposite side thereof from the extension 54 adapted for wiping engagement by a contact 57 of a block 58 carried by such extension.

It will be understood that the source of electrical supply for the electro-magnet 37 is connected with the contacts 56 and 57 by means of wires also attached to the binding-posts 68 of the electro-magnet 37, substantially 59 so that during the entire movement of the lever 21, the electrical connections for the electro-magnet 37 will be complete, only being interrupted when the neutral end portion 60 of the segment 55 is reached by the lever extension 54 and its block 58.

An air valve 61 is provided at the neutral end 60 of the segment for controlling the air supply to the pipe 51 connected to the valve, it being noted that the valve is normally open to the source of air supply from a pipe 69 and the supply of air through the pipe 51 constant during the movements of the lever 21 and until the extension 54 comes into engagement with the operating head 62 of the valve 61 and at which time the air supply is cut off. Any suitable source of supply for the compressed air may be provided such as an air tank in connection with a suitable compressor and by the present arrangement the electro-magnet 37 will be energized and the nozzles 52 in operation during the swinging operative movement of the casing 15 and the saw 10 but the electro-magnet will automatically be deenergized and the air pressure interrupted when the casing 15 returns to its normal position.

It will be understood that the side 34 of the saw cover casing 15 is adapted to be

locked closed by means of a suitable lock 68 while the sides of the trough 27 may be connected by hinges 69 with the basin 39.

A serviceable spark collector for saws is arranged wherein substantially all of the sparks are collected and prevented from doing any damage while the collecting operation is entirely automatic in its actuation and does not interfere with the usual operation of saw but adds to the efficiency thereof.

What I claim as new is:—

1. A spark collector for saws comprising an electro-magnet adapted for positioning adjacent a saw, a pneumatic draft appliance directed toward the said electro-magnet whereby oncoming metallic particles are baffled adjacent the electro-magnet.

2. In combination with a cutting saw, an electro-magnet arranged adjacent the cutting area thereof and a pneumatic draft appliance directed toward the said electro-magnet against the path of travel of sparks generated by the saw.

3. In combination with a saw, a casing therefor arranged with a cut-away mouth portion, an electro-magnet adjacent the said mouth and a pneumatic nozzle carried by the casing rearwardly of the mouth directed toward the electro-magnet.

4. In combination with a saw, a casing therefor arranged with a cut-away mouth portion, an electro-magnet adjacent the said mouth, a pneumatic nozzle carried by the casing rearwardly of the mouth directed toward the electro-magnet, shiftable mounting means for the saw, a controlling valve for the pneumatic means and an electrical switch for the electro-magnet and means adapted for closing the valve and opening the switch when the saw is in its normally inoperative position.

5. A spark collector comprising in combination with a swinging rotary saw, a casing surrounding the same having a hinged side and adapted for swinging movement with the saw and further having a cut-away mouth exposing the forward cutting portion of the saw, a trough within which the casing is shiftably arranged, a saw-run transversely positioned with respect to said trough having a transverse slot in advance of the saw, an electro-magnet carried by the trough beneath the saw and pneumatic nozzles carried by the hinged side of the casing directed toward the electro-magnet.

6. A spark collector comprising in combination with a swinging rotary saw, a casing surrounding the same having a hinged side and adapted for swinging movement with the saw and further having a cut-away mouth exposing the forward cutting portion of the saw, a trough within which the casing is shiftably arranged, a saw-run trans-

versely positioned with respect to said trough having a transverse slot in advance of the saw, an electro-magnet carried by the trough beneath the saw, pneumatic nozzles carried by the hinged side of the casing directed toward the electro-magnet, a normally resiliently closed hood forwardly of said mouth overlying the run, a propelling finger carried by the casing forwardly of the mouth within the said hood, a spring-pressed follower in normal engagement with the lower rear portion of the casing and automatic controlling means for the said electro-magnet and nozzles.

7. A spark collector comprising in combination with a swinging rotary saw, a casing surrounding the same having a hinged side and adapted for swinging movement with the saw and further having a cut-away mouth exposing the forward cutting portion of the saw, a trough within which the casing is shiftably arranged, a saw-run transversely positioned with respect to said trough having a transverse slot in advance of the saw, an electro-magnet carried by the trough beneath the saw, pneumatic nozzles carried by the hinged side of the casing directed toward the electro-magnet, a normally resiliently closed hood forwardly of said mouth overlying the run, a propelling finger carried by the casing forwardly of the mouth within the said hood, a spring-pressed follower in normal engagement with the lower rear portion of the casing, a lever adapted for shifting the said casing and saw, a segment adjacent the swinging end of said lever, an air controlling valve for said nozzles adjacent one end of the segment adapted for operative closing engagement by the said lever when the saw is in its inactive position, an electrical terminal plate for said magnet carried by said segment terminating in spaced relations with the said valve carried under thereof and the other terminal of said electro-magnet carried by said lever end in contact with said plate throughout the length of the latter and out of contact with said plate when the lever is positioned adjacent the said valve.

8. A spark collector comprising in combination with a swinging rotary saw, a casing surrounding the same having a hinged side and adapted for swinging movement with the saw and further having a cut-away mouth exposing the forward cutting portion of the saw, a trough within which the casing is shiftably arranged, a saw-run transversely positioned with respect to said trough having a transverse slot in advance of the saw, an electro-magnet carried by the hinged side of the casing directed toward the electro-magnet, a lever adapted for shifting the said casing and saw, a segment

adjacent the swinging end of said lever, an air controlling valve for said nozzles adjacent one end of the segment adapted for operative closing engagement by the said lever when the saw is in its inactive position, an electrical terminal plate for said electro-magnet carried by said segment terminating in spaced relations with the said

valve carried by said lever end in contact with said plate throughout the length of the 10 latter and out of contact with said plate when the lever is positioned adjacent the said valve.

In testimony whereof I affix my signature.

JAMES T. JOHNSON.
